UNITED STATES PATENT OFFICE.

WILLIAM INTEMANN, OF BROOKLYN, NEW YORK, ASSIGNOR TO AMERICAN LITHOGRAPHIC COMPANY, OF NEW YORK, N. Y., A CORPORATION OF NEW YORK.

PROCESS OF BANDING CIGARS.

Application filed April 29, 1925. Serial No. 26,624.

This invention relates to cigar bands, such as are secured about a cigar to carry the name of the cigar, the maker thereof, or both, and other pertinent matter, and particularly to processes of banding cigars.

The object of my improvements is to provide a cigar band simple in construction, economical of manufacture and of wide applicability. Other features of usefulness will appear later herein.

With these ends in view my improvements comprise features illustrated in their preferred embodiment in the accompanying drawing, wherein:

Figure 1 is a plan view of a strip of sheet material adapted to be wrapped about a cigar with the ends overlapping and secured together. Fig. 2 is an edge view of said strip of Fig. 1. Fig. 3 is a relatively short strip or portion of sheet material adapted for carrying a legend and for being secured to the strip of Fig. 1. Fig. 4 is an edge view corresponding with the showing of Fig. 3. Fig. 5 is a plan view showing the portion of sheet material of Fig. 3 secured to the strip of Fig. 1. Fig. 6 is an edge view of what is shown in Fig. 5. Fig. 7 is a plan view similar to that of Fig. 5, showing a legend bearing portion of a different shape from that of Fig. 3. Fig. 8 is an edge view of what is shown in Fig. 7. Fig. 9 is similar to the showing of Fig. 7 but with the long strip of indefinite length. Fig. 10 is a plan view of a portion of a cigar about which the strip of Fig. 1 has been wrapped and secured. Fig. 11 is a similar view to that of Fig. 10 but showing the legend bearing portion applied to the encircling strip. Fig. 12 is an end view of a cigar about which is wrapped and secured a strip of indefinite length. Fig. 13 shows the wrapped cigar with the surplus portion of the strip severed and removed. Fig. 14 is similar to Fig. 13 but with the legend bearing portion applied to the long strip. Fig. 15 shows a plurality of cigars each bearing an encircling strip and packed in a box. Fig. 16 shows one of the packed cigars of Fig. 15 removed and supplied on its upper face with the legend bearing portion. The scale of all the figures is the same and about full size, the thickness of edge views of the bands being exaggerated to show details more clearly.

My improved cigar band includes two members, the first, a cigar encircling mem-

ber, preferably of paper and which may be of any convenient width, and which is adapted to be secured about the cigar by an adhesive between the overlapping portions of said strip. The second member, a relatively short strip or portion, preferably of paper and adapted to carry a legend and which portion is secured to the cigar encircling portion, preferably by an adhesive.

As commonly used, cigar bands comprise a relatively large center portion and relatively narrow strips extending in opposite directions therefrom, said narrow strips being adapted for overlapping and for being secured together by an adhesive. These bands are commonly printed in several colors and embossed, said printing and embossing usually extending to or nearly to the ends of the narrow portions. The total length of a band of this character varies from two to three and one-quarter inches according to the size of the cigar to which it is to be applied. The cost of paper, printing and embossing is a material item in the expenses of cigar manufacture. Furthermore, because of the wide variety in sizes of cigars, a great quantity of different lengths of bands are carried in stock by the cigar manufacturers. It is one of the requirements in cigar manufacture and packing, that the legend carrying portion, trademark or other insignia shall be so placed as to appear on the top face of the cigar when the cigars are packed in boxes. After the cigars are packed in boxes they assume a variety of cross-sectional shapes varying widely from their original approximately cylindrical forms. Also, it is customary to band the better quality of cigars after they have been packed, they being removed from the box for that purpose and after being banded, are replaced in the box in their original order. The banding of packed cigars is an operation requiring skill and care, when done by hand, and requires an elaborate and complicated machine, if done by machinery. By my improvements, great economy in printing, gilding and embossing may be had, as my cigar encircling strip can be of unprinted, plain paper, or at most, may be simply printed in one operation, as that strip shows but little or not at all when the cigars are packed in the box. Also, the legend bearing portion, because of its small size relatively to the cigar bands at present used, may be

printed with at least twice as many to the sheet as now possible.

In applying my improved band mechanically, much simpler machines may be employed than are required for the bands at present used, as the encircling strip may be applied without reference to what is eventually to be the top of the cigar in the box and preferably may be applied from a continuous strip, which is a relatively simple matter. Also, by the use of a cigar encircling strip of uniform width and uniform character, it is immaterial, within wide limits, how much overlap occurs, whereby one length of band is applicable to a wide range in size of cigars. If this encircling strip is taken from a continuous roll, as proposed, still greater economy of material may be had, as each cigar, irrespective of its size, is provided with a length of band adapted to its particular need and the surplus portion severed therefrom.

Then when the cigars are ready to receive the legend bearing portion this can be applied very rapidly by relatively simple mechanism. Also because these legend portions may be of one standard size for all sizes of cigars the manufacturer is not required to carry in stock a variety of sizes thus greatly contributing to economy and the elimination of trouble.

Referring now to the drawing the earlier brief description of the figures may be supplemented by stating that the band strip B of Figs. 1 and 2 may be supplied with an adhesive 2 at one end if desired to be moistened when the band is applied to the cigar C as in Fig. 10. Also the legend carrying portion L of Figs. 3 and 4 may be supplied with an adhesive 3 to be moistened before said portion is applied to strip B, Figs. 7, 9, 11, 14 and 16. The modification of Figs. 7 and 8 illustrates the adaptability of my improvements to a different shape and size of legend portion L¹, and wherein band strip B¹ may be of different widths as desired. In Fig. 9 a strip B² of indefinite length is shown and which strip may bear any desired advertising matter, such as the cigar maker's initials or name. In the end view of Fig. 12 the strip of Fig. 9 is shown wrapped about the cigar C and the leading end 4 of the strip affixed to the overlapping portion thereof. In Fig. 13 the surplus portion of strip B has been severed and removed.

The cigar is now ready for preliminary

packing in a box, if desired, to give the cigar its permanent shape when boxed, see Fig. 15. Then the packed cigar may be removed from the box and the legend portion L applied and secured to the upper face of the encircling strip, Fig. 16, ready to be re-packed, face up.

I claim:

1. That improvement in the process of banding cigars comprised in encircling the cigar with a strip of paper in overlapping relation, securing by an adhesive one end of said strip to the overlapped portion, and attaching by an adhesive a legend carrying portion of paper to said cigar encircling strip.

2. That improvement in the process of banding cigars of various sizes comprised in encircling each cigar with the end portion of a strip of paper of indefinite length in overlapping relation, securing the leading end of said strip by an adhesive to that portion of said strip overlapping said leading end, severing the surplus portion of said strip from the cigar encircling portion irrespective of the length used to encircle the cigar, and attaching by an adhesive a legend carrying portion of paper to said cigar encircling strip.

3. That improvement in the process of banding cigars comprised in encircling the cigar with a strip of paper in overlapping relation, securing one end of said strip by an adhesive to the overlapped portion, packing said strip encircled cigar with others of its fellows, removing said packed cigar, and attaching by an adhesive to the upper face of the encircling strip a legend carrying portion of paper.

4. That improvement in the process of banding cigars comprised in encircling a cigar with the end portion of a strip of paper of indefinite length in overlapping relation, securing by an adhesive the leading end of said strip to that portion of said strip overlapping said leading end, severing the surplus portion of said strip from the cigar encircling portion irrespective of the length of said encircling portion, packing said strip encircled cigar with others of its fellows, removing said packed cigar, and attaching by an adhesive to the upper face of the encircling strip a legend carrying portion of paper.

In witness whereof, I hereby affix my signature this 28th day of April, 1925.

WILLIAM INTEMANN.
